UNITED STATES PATENT OFFICE.

FRANK H. LA PIERRE, OF EAST ORANGE, NEW JERSEY.

DESIGN FOR A CLOTHES-BRUSH.

SPECIFICATION forming part of Design No. 28,682, dated May 24, 1898.

Application filed April 21, 1898. Serial No. 678,396. Term of patent 7 years.

To all whom it may concern:

Be it known that I, FRANK H. LA PIERRE, a citizen of the United States, residing at East Orange, in the county of Essex and State of New Jersey, have invented and produced a new and original Design for a Clothes-Brush; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a plan of a clothes-brush of my new design; and Fig. 2 is a sectional view of the same, taken on line *x* of Fig. 1.

As shown in the drawings, the leading or material feature of my newly-designed clothes-brush consists in the "polka-dot" ornamentation displayed on the ground of the clothes-brush back.

In said drawings, *a* indicates the body of the brush, which is approximately oblong in plan, the opposite longer side edges *b* being parallel and the ends *c* being convexly curved. The back surface of said clothes-brush body is plain at the center, and the edges are convexly rounded, as indicated at *b* in Fig. 2. The plain surface of the back is ornamented with polka-dots *e*, distributed widely apart over said surface, and at the center of the back is a larger polka-dot ornament *f*.

Having thus described the invention, what I claim as new is—

The design for a clothes-brush as herein shown and described.

In testimony that I claim the foregoing I have hereunto set my hand this 18th day of March, 1898.

FRANK H. LA PIERRE.
